UNITED STATES PATENT OFFICE.

WILLIAM PATRICK DEVINE, OF DORCHESTER, MASSACHUSETTS.

SHOE-BUTTON.

1,292,588.

Specification of Letters Patent. Patented Jan. 28, 1919.

Application filed September 23, 1915, Serial No. 52,522. Renewed December 6, 1918. Serial No. 265,803.

To all whom it may concern:

Be it known that I, WILLIAM P. DEVINE, a citizen of the United States of America, and a resident of Dorchester, in the county of 5 Suffolk and State of Massachusetts, have invented certain new and useful Improvements in Shoe-Buttons, of which the following is a specification.

This invention relates to buttons and particularly to that class of buttons commonly used on shoes, gaiters, etc., the body portions of which are made of some hardened plastic material and which are provided with metal eyes secured to said body portions.

One object of the present invention is to save material, the body portion of each button being provided with depressions on the outer and inner faces thereof, the outer depression having a central recess adapted to 10 receive the head of a metal pin, the shank of which extends completely through said body portion and is bent to form an eye with its point embedded in the inner face of said body portion, thereby preventing 15 the pin from turning therein.

Another object of the invention is to provide the end face of the body portion with an annular recess, the edge of the outer wall of which bears upon the material and there- 20 by prevents any portion of the inner face of the body portion contacting with the eye of the buttonhole and causing its stitches to be worn.

A further object of the invention is the 25 provision of a disk inserted in the outer depression adapted to cover the head of the pin, this disk preferably being of a different color of material and adding materially to the artistic appearance of the button.

The invention further consists in certain 30 novel features of construction and arrangement of parts which will be thoroughly understood by reference to the description of the drawings and to the claims herein- 35 after given.

Of the drawings:

Figure 1 represents a plan view of a button embodying the features of the present invention.

Fig. 2 represents a transverse section of 40 the same, and

Fig. 3 represents a horizontal section of 45 the same, the cutting plane being on line 3-3 on Fig. 2 looking in the direction of the arrow thereon.

Similar characters designate like parts

throughout the several figures of the drawings.

In the drawings, 10 represents a body portion of a button which is preferably made 60 of celluloid or some similar hardened plastic material. It is provided with a central opening 11 extending therethrough and its outer face has a depression 12 therein provided with a central recess 12* in which is 65 positioned the head 13 of a pin, the shank of which extends through said central opening 11 and is bent over to form the eye 14. At one side of the central opening 11 is a recess 15 in which is positioned the point 16 70 of the shank of the headed pin 13-14. The insertion of the point 16 in this depression 15 materially strengthens and stiffens the eye 14 and makes it possible for said eye to be subjected to a greatly increased strain. 75 At the same time the positioning of the point 16 in the recess 15 prevents the pin from turning in the central opening 11 extending through the body portion 10. The inner face of the body portion is provided 80 with a hub 17 surrounded by an annular depression 18, the outer wall of which terminates at 19 forming a rounded annular edge considerably beyond the face of the hub portion 17 so that when the button is attached 85 to a shoe or other article the face of the hub 17 will never contact with the stitches of the eye of the buttonhole and injure said stitches by rubbing action thereon.

By having the depression 12 in the outer 90 face and the annular depression 18 on the inner face the body portion 10 may be made up from sheet celluloid and compressed into the form shown in the drawings, thereby saving considerable material in the manu- 95 facture of the buttons.

In the depression 12 is positioned a disk 20 of some material preferably distinctive in color or design from the body portion 10 of the button, the disk 20 serving to hide 100 from view the head 13 of the pin 14 and at the same time add greatly to the ornamental appearance of the button.

By inserting disks 20 of different artistic designs and colors a great variety of buttons 105 may be made with the same style of body portion 10.

It is obvious that the body portion 10 may also be varied in color or provided with artistic designs.

The disk 20 may be of celluloid, leather, cloth, or any other flexible material, and is

preferably formed over a circular metal plate 21, which before insertion is slightly crowned as indicated in dotted lines in Fig. 2.

The edge of the disk 20 is folded over the 5 edge of the plate 21 and when forced into the depression 12 by a die the outer surface is flattened and the edge of the disk 20 jammed against the wall of the depression 12 and locked securely in position.

10 It is believed that the many advantages of this invention will be fully understood from the foregoing description.

Having thus described my invention, I claim:

15 1. A button comprising an annular body portion having a flat bottomed depression in its outer face having a vertical wall and provided with a central recess, a pin extending through said body portion with its head positioned in said recess and its shank bent 20 to form an eye, said head having a flat end flush with the bottom of said depression, a disk inserted in said outer depression and covering the head of said pin, and a metal

plate inclosed in said disk and adapted to 25 lock said disk against the vertical wall of said outer depression and with its outer face flush with the outer end of said body portion.

2. A button comprising an annular body portion having a flat bottomed depression in its outer face having a vertical wall provided with a central recess, a pin extending through said body portion with its head positioned in and fitting said recess and its shank bent to form an eye, said head having 30 a flat end flush with the bottom of said depression, a flat disk inserted in said outer depression and covering the head of said pin, and means for locking the edge of said disk against the wall of said depression and 35 with its outer face flush with the outer end of said body portion.

Signed by me at 4 Post Office Sq., Boston, Mass., this 15th day of September, 1915.

WILLIAM PATRICK DEVINE.
